ELMER HEDEEN, OF MANSFIELD, OHIO, ASSIGNOR TO THE HUGHES-KEENAN COMPANY, OF MANSFIELD, OHIO, A CORPORATION OF OHIO.

STAIR CONSTRUCTION.

Application filed August 23, 1927. Serial No. 214,955.

This invention relates to the construction of stairs, and among other objects, aims to provide an extremely simple and economical, strong and durable construction which is especially useful for the stairways of public buildings.

In the accompanying drawings forming a part of this application there is shown a preferred embodiment of the invention.

10 In said drawings:

Fig. 1 is a vertical sectional elevation of a portion of a stairway;

Fig. 2 is a vertical cross section; and

15 Fig. 3 is a detail showing how the parts are assembled.

Referring more specifically to the drawings, there is shown a pair of stringers 5 supporting the steps, each stringer being preferably of sheet metal and having an inturned flange 6 along its underside. The steps proper, which embody the improvements 20 rest partly on the two flanges 6 and partly on tie rods 7 passing through the stringers and binding them together, as will be described.

The steps are built up from a series of interlocking sheet metal elements each having a length equal to the distance between the stringers and each being bent at right angles 25 to provide a horizontal tread or tread-supporting portion 8 and a vertical riser portion 9, with the corner or angle 10 secured at opposite ends by bolts or screws 11 to the flanges 6. The sheet metal step elements are interlocked at the front of each tread, the interlocking being accomplished at the time the stairway is installed, and preventing any relative lateral or up and down movements of the step elements. Longitudinal movements are prevented by the stringers. The 30 interlocking is permitted because of the shape of the parts and the way they are assembled, and is accomplished without employing any movable fastening parts, hence without any labor other than the inevitable labor of bringing the parts together. The elimination of 35 this labor results in a rapid building of the stairway, thus increasing the profits of the builder, and facilitating completion of the 40 job.

As shown, each tread or tread-supporting portion 8 is substantially plane except at the forward edge, where an upstanding flange 12 is provided, as by bending. The upper end 45 of each riser portion 9 is bent to provide a

flange 13 which is vertical and offset relative to the riser portion, being located in front of the plane of the riser. At its upper edge, each riser flange 13 is bent rearwardly substantially at right angles, as at 14, not only to enclose the flange 12 of the adjacent tread portion 8, but also to protect the tread and aid in holding it, and also to carry means for interlocking with the adjacent flange 12.

As shown, each flange 14 carries on its underside a rod 15 providing a bead, spaced a small fraction of an inch from flange 13, and secured as by spot welding 16. As the flange 13 is slightly taller than flange 12, the latter will be received between the flange 14 and the horizontal offset portion 17, permitting manual assembly of the step elements, as shown in Fig. 3.

With the parts assembled as in Fig. 1, it will be clear that any stress tending to separate any two interlocked step elements will be resisted by contact of the bead 15 with flange 12, which is stiffened by flange 13. The treads are carried by the tie rods 7, the offset portions 17 and the flanges 6. Any tendency 50 of the treads 8 to yield under loads results in a very slight rocking on tie rods 7, thrusting the flange 12 up against flange 14, which tends to pull up the riser portion of the lower step element. Most of the load on each 55 tread is transferred directly to the tie rods 7, which are of adequate strength, particularly when tightened to the stringers by their nuts 18. The tie rods subject the step elements, particularly at the joints, to a compressive 60 stress, thus contributing to the rigidity and strength of each joint. The bead 15 also plays a part in stiffening the flange 14, which cannot bend downwardly under a load to any appreciable extent because of the adjacent flanges 12, 13. It will be clear that flange 65 14 eliminates a nosing insert.

The treads 19 may be of any material, and as shown are so placed as to be supported by the tread-supports 8, and so as to be confined between and subjected to compressive stresses from the stringers 5. The treads may be positioned either before or after erection of the stairs, according to the material they are made of, and when in position, serve to reinforce the tread supports as well as to brace the flanges 12, 13 and the interlocked joint. Obviously, the flanges 14 will aid in holding the treads 19.

Obviously the present invention is not re-

stricted to the particular embodiment thereof herein shown and described. Moreover, it is not indispensable that all the features of the invention be used conjointly, since they may 5 be employed advantageously in various combinations and sub-combinations.

What I claim is:—

1. A sheet metal element for the construction of stairs, comprising a tread portion 10 and a riser portion; an upstanding flange extending longitudinally along the outer edge of the tread portion substantially at right angles thereto; an inturned flange provided at the upper end of the riser portion 15 to project somewhat over the tread portion of the adjacent stair element; and a bead made fast underneath said inturned flange so spaced from the vertical plane of the adjacent riser portion that there is sufficient

room to receive the upstanding flange of the 20 adjacent, higher stair element.

2. A sheet metal element for the construction of stairs, comprising a tread portion and a riser portion; an upstanding flange extending longitudinally along the outer edge of the 25 tread portion substantially at right angles thereto; an offset flange provided at the upper end of the riser portion and joined thereto by a shoulder which aids in the assembly and support of the adjacent, higher tread; 30 an inturned flange at the upper edge of said offset flange; and a rod spot-welded underneath said inturned flange to hold the upstanding flange of the adjacent, higher step element, when the stairs are assembled. 35

In testimony, that I claim the foregoing as my own, I have hereto affixed my signature.

ELMER HEDEEN.
